UNITED STATES PATENT OFFICE.

WILLIAM MARSHALL, OF DETROIT, MICHIGAN, ASSIGNOR TO BRIGGS MANUFACTURING COMPANY, OF DETROIT, MICHIGAN, A CORPORATION OF MICHIGAN.

HINGE SUPPORT.

Application filed September 8, 1924. Serial No. 736,643.

This invention relates to vehicle bodies and refers more particularly to supports for door hinges and the like.

An object of the invention is to provide a strong and durable post or pillar which is preferably formed of channel members of minimum weight that are preferably connected together so as to provide a hollow post that is sealed on all sides.

10 Another object is to provide a post having a strengthening member that preferably reinforces the securing portion for the hinge.

With the above and other objects in view, the invention consists of certain novel features of construction, combination and arrangement of parts as will be more fully described and particularly pointed out in the appended claims.

15 In the accompanying drawing:—

20 Figure 1 is a fragmentary side elevation of a vehicle body embodying my invention;

Figure 2 is a sectional view taken on line 2—2 of Figure 1;

25 Figure 3 is a sectional view taken on line 3—3 of Figure 2;

Figure 4 is a detail perspective view of the reinforcing member;

30 Figure 5 is a perspective view of one of the channel members of the post and showing a slightly modified form of reinforcing member;

Figure 6 is a sectional view through the construction shown in Figure 5;

35 Figure 7 is a view similar to Figure 5, but showing another modification;

Figure 8 is a sectional view through the construction shown in Figure 7;

Figure 9 is a top plan view of the reinforcing member shown in Figure 7;

40 Figure 10 is a top plan view of the attaching plate shown in Figure 7.

Referring now to the drawing in which like characters of reference designate corresponding parts throughout the several views, the numeral 1 designates a motor vehicle body of the closed type having a suitable post or pillar 2 to which a metallic post 3 of a door 4 is preferably pivotally connected by means of suitable hinges 5.

50 For the purpose of forming a post or pillar having great strength with minimum weight, the post 3 is preferably formed of two channel members 6 and 7 respectively. One side 8 of the channel 6 is preferably of a width substantially equal to the width of

the post 2 and is preferably provided with openings 9 which receive the securing elements 10 for one section 11 of each hinge, while the other side 12 is preferably relatively narrow and is provided with a laterally extending flange 13. The channel 7 is preferably provided with a relatively narrow side 14 that engages the outer face of the flange 13 and is also preferably provided with a laterally extending flange 15 that is secured to the narrow side 12 of the channel 6. The base 16 of the channel 7 is preferably parallel to the relatively wide side 8 of the channel 6 and preferably curves into a relatively wide side 17 which is preferably parallel to the base 18 of the channel 6 and that is preferably provided with a return-bent flange 19 that receives a flange 20 projecting laterally from the forward edge of the wide side 8 of the channel 6.

55 The base 16 and outer side 17 of the channel 7 are preferably enameled so as to form an outer panel or finish strip for the vehicle body while a suitable finish strip 21 is preferably secured to the flange 15 and preferably cooperates with the narrow side 14 of the channel 7 to receive a clip 22 holding the resilient channel 23 for the usual sashless glass panel 24 of the door window.

60 For strengthening the post 3, as well as reinforcing the securing portion for the hinged section 11, I preferably provide an elongated substantially U-shaped member 25 having upwardly and downwardly extending flanges 26 that are secured to the narrow side 12 of the channel 6. The base 27 of the U-shaped member engages the wide side 8 of the channel 6 and is preferably provided with openings 28 that receive the securing elements 10 for the hinged section 11. Suitable nuts 29 are preferably threaded onto the securing elements for retaining the base 27 of the U-shaped member against the side 8 of the channel 6. The parallel sides 30 of the U-shaped member constitute braces between the flanges 26 and the base 27 and cooperate therewith to strengthen the post construction.

65 In Figures 5 and 6 I have shown a slight modification wherein the base 31 of the U-shaped reinforcing member 32 is preferably provided at its outer and inner edges with struck-out tongues 33 which are preferably bent over a metal attaching plate 34. With this construction, the securing elements 35

for the hinged section 36 preferably extend through aligned openings 37 and 38 respectively in the side 39 of the channel member 40 and in the base 31 of the reinforcing member 32 and threadedly engage the attaching plate 34. If desired suitable nuts (not shown) may be threaded onto the securing elements 35 against the attaching plate 34.

In Figures 7 to 10 inclusive, I have shown 10 still another modification wherein the hinge section 50 preferably engages the inner face 51 of the wide side 52 of the channel member 53 and is embraced by an offset portion 54 of the base 55 of the U-shaped reinforcing member 56. As shown in Figure 8, the base 55 of the reinforcing member is preferably provided at its outer and inner edges with struck-out tongues 57 which correspond to the tongues 33 and are bent over a metal 15 attaching plate 58 to which the securing elements 59 for the hinge section 50 preferably extend. 20

While it is believed that from the foregoing description the nature and advantages 25 of the invention will be readily apparent, I desire to have it understood that I do not limit myself to what is herein shown and described and that such changes may be resorted to when desired as fall within the 30 scope of what is claimed.

What I claim as my invention is:—

1. The combination with a post including a channel member, of a reinforcing member for said channel member, an attaching plate 35 on said reinforcing member, tongues on said reinforcing member holding said attaching plate, a hinge, and means engaging said attaching plate for securing said hinge to said channel member.
2. The combination with a post including a channel member, of a reinforcing member for the post extending between opposite sides of the channel member, an attaching plate, means on the reinforcing member 45 holding said plate, a hinge, and headed elements engaging said plate for securing the hinge to the channel member.
3. The combination with a post including

a channel-shaped member and a hinge secured to one side wall of said member, of a 50 U-shaped reinforcing member extending transversely of said channel-shaped member and having vertical flanges, the base of said U-shaped member being secured to the side wall of the channel adjacent to said 55 hinge, the flanges of said member being secured to the opposite wall of the channel.

4. The combination with a post including a channel-shaped member, of a channel-shaped reinforcing member extending transversely of said channel-shaped member aforesaid, an attaching plate between the sides of the channel-shaped reinforcing member, means for securing said plate to the base of said reinforcing member, a hinge, 60 and means engaging said plate for securing said hinge to the first mentioned channel-shaped member.

5. The combination with a post including a channel-shaped member, and a hinge having a portion extending along one side wall of said channel member, of reinforcing means for said post including a brace located within the channel of said member in a horizontal plane with said hinge and having 75 portions secured to the opposed side walls of said channel member, and securing means for the reinforcing member and hinge including elements extending through the first mentioned side wall aforesaid of said channel member.

6. The combination with a post including a channel-shaped member, and a hinge having a portion extending along one side wall of said channel member, of means for reinforcing said post including a brace extending between two walls of said channel member, and a common securing means for said hinge and reinforcing member including elements extending through registering openings in said hinge, reinforcing member, and the first mentioned wall aforesaid of said channel member.

In testimony whereof I affix my signature.

WILLIAM MARSHALL.
